TILTING DEVICE FOR DRUM MELTING FURNACES

Karl Gottschalk, Csepel, Hungary

Application February 16, 1938, Serial No. 190,796
In Germany February 25, 1937

2 Claims. (Cl. 263—33)

For quick charging and discharging, drum melting furnaces adapted to rotate about their longitudinal axis are, as is known, tiltable about a transverse axis passing through the centre of gravity of the furnace. For this purpose, the tiltable frame carrying the furnace is mounted either by means of two toothed segments situated on both sides of the furnace in bearing frames located laterally of the furnace or by means of cradles mounted on the tiltable frame on both sides of the furnace and cooperating with guide rollers.

Both tilting devices possess the disadvantage that they cover the furnace laterally, more or less, and render the sides of the furnace inaccessible, particularly when the furnace is constructed so as to be set in an absolutely vertical position for the purpose of ramming the lining, this construction being particularly very disadvantageous when the furnace is to be provided with lateral devices for the introduction of air or fuel, or of reducing means for coal dust. To obviate this disadvantage, it has been proposed to lower the tilting devices to such an extent as to bring the tilting axis below the furnace, whereby, however, the centre of gravity of the furnace is raised high above the tilting axis, and the working safety of the furnace under the considerable weights involved is impaired.

The object of the invention is a tilting device, which will enable absolutely vertical positioning of the drum, and which tilting device may be accommodated completely below the drum, even when the tilting axis is high, that is to say on a level with the centre of gravity of the drum, this drum thus being rendered freely accessible from both longitudinal sides.

The new tilting device is characterized in that the furnace drum, by means of two toothed segments, mounted on both sides below the rotary frame of the drum, rests on roller chains which are each passed over a stationary roller track having two guide drums and a toothed driving wheel.

It has indeed already been proposed to employ roller chains for supporting rotary drum furnaces, not for the purpose of tilting the drum, however, but for the purpose of rotating the drum. In this device the roller chains did not serve simultaneously for driving the furnace but, on the contrary, a specially provided crown gear was arranged. According to the invention, however, the roller chains serve simultaneously both as a supporting and as a driving means for the tilting movement, whereby, in view of the con-

siderable masses which are to be moved, a very simple, durable and reliable tilting device is provided.

The drawing shows diagrammatically a constructional example of a rotary drum melting furnace provided with the new tilting device.

Figure 1 is a side view partly in section.

Figure 2 is an end view partly in section along the line 2—2 of Figure 1, and

Figure 3 is a side view on a smaller scale showing the drum set in an absolutely vertical position for ramming the lining.

The tilting device comprises the stationary, hollow base frames *a*, *a*, each having a cylindrical roller track around which tracks are passed the endless link chains *h*, the link pins of which chains carry on their outer ends rollers *i* running in the tracks *a*. The furnace drum *d* is mounted in a known manner on the tiltable support by means of track rings *e*, *e* supported on rollers *f*, and is held down loosely by bands *g*. The tiltable support is provided on both its sides and below the drum with sprocket sectors *b* extended over an arc of substantially 120° and resting with their periphery on their chains, so that the sprocket sectors are mounted coaxially with the roller tracks. Each chain *h* is constructed as a double chain and the sprockets *j* of the sectors *b* project into the gap between the chains and engage the link pins of the chains. The link chains are passed around guide drums *k* and driving wheels *n*, which wheels are driven by a motor *m*.

By rotation of the driving wheels in the direction of the arrow *p*, the chains *h* and the sprocket sectors *b* are moved in the direction of the arrow *q* through the bearing bed formed by the roller tracks *a*, the drum thus being tilted. Despite the fact that the sprocket sectors *b* embrace an arc of 120° and the tilting axis *o* is in the centre of gravity of the furnace, the entire tilting device is situated below the drum, so that the latter remains quite freely accessible from both sides. As will be seen in Figure 3, the drum may be set perfectly vertical for the purpose of ramming the lining, the drum then being supported on either side by struts *v* which engage at their one end the spindle *r* of the guide rollers *k* and at their other end a pivot *s* situated on a bracket *t* inserted between the track rings *e* of the drum. Tilting may be effected in both directions and until the vertical position is reached.

What I claim is:—

1. A drum melting furnace device including in combination a furnace drum, means for rotating

said drum about its longitudinal axis, a tiltable support, means for mounting said drum and said rotating means on said tiltable support, two stationary hollow base frames associated with said support,—one frame on either side of said support—each of said base frames being provided with a cylindrically shaped track at its upper surface and a roller chain adapted to ride upon said track and to pass the hollow space of said base frame, a common drive for the roller chains of both said base frames, said tiltable support being provided with two sprocket sectors, one at either side, said sectors being extended downwardly from said support and below said drum, each of said sprocket sectors being co-axial and in alignment with one of said base frame tracks and adapted to be supported and to be engaged by the upper branch of the roller chain riding upon said track.

2. A device as set forth in claim 1, said rotating means including a pair of peripheric track rings fast on said drum, and roller pairs associated with said track rings and adapted to support and to rotate same, said device further including two struts and two brackets, one of each on either side of said support, a spindle mounted on either base frame, said brackets being inserted between said track rings at either side of said drum each, said brackets being provided each with a pin protruding outwardly and in the tilting axis of the drum, said struts each engaging at their one end one of said bracket pins and at their other end one of said spindles, for the purpose of ensuring by means of said struts the upright position of said drum.
